UNITED STATES PATENT OFFICE.

GEORGE W. FRANCIS, OF SHELBYVILLE, INDIANA.

FLOOD-GATE.

SPECIFICATION forming part of Letters Patent No. 272,872, dated February 27, 1883.

Application filed September 18, 1882. (No model.)

To all whom it may concern:

Be it known that I, GEORGE W. FRANCIS, of the town of Shelbyville, county of Shelby, and State of Indiana, have invented certain new and useful Improvements in Flood-Gates, 5 of which the following is a specification.

The object of my said invention is to produce a gate or fence for use in fencing across creeks, rivers, &c., which shall be permanent 10 and durable, and also capable of adjustment to suit the varying height of the water. This object is accomplished by planting mud-sills in the banks at about low-water mark, setting posts therein, providing the same with slides, 15 mounting a gate or section of fence in said slides, and providing means whereby said fence can be elevated or lowered in said slides, as will hereinafter be more particularly set forth.

Referring to the accompanying drawings, 20 which are made a part hereof, and on which similar letters of reference indicate similar parts, Figure 1 is a side elevation of a section of fence embodying my invention; Fig. 2, a top plan of the same; Figs. 3 and 4, elevations, 25 respectively, of the two ends, and Fig. 5 a view of a lever which may be used in raising the fence.

In said drawings, the portions marked A represent the mud-sills on which my improved 30 fence is mounted; B, the posts; C, the wires of the gate or fence; D, ropes or cords by which the fence may be elevated, and E a hook-lever which may be used for the same purpose.

The mud-sills A are planted in the banks of the stream at about low-water mark, and are 35 extended back into the bank far enough to insure that they remain firmly and securely in position.

The posts B are four in number—two at each 40 end—and are firmly secured to the mud-sills. Braces B' are placed upon the inside of these posts, as shown, to prevent said posts from being drawn toward each other by the fence, 45 or guys are attached to the top of the posts and extended back to an anchoring. In case of very high posts, which would be used in cases where the rise and fall of the water in the stream is considerable, the guys will probably be found preferable, and in some cases 50 both guys and braces may be found desirable. The space between the two posts at each end

is sufficient to allow the wires of which the fence is preferably composed to pass freely between them. Upon the outer side of each post 55 is secured a strip, B². Said strips, with the faces of the posts, form slides in which the stiles c of the fence slide.

The gate or fence is composed of a stile, c, at each end, and wires or rails C connecting them, and is adapted to be elevated or depressed, and thus be kept in sufficiently close proximity to the water at all times, notwithstanding its varying height, without being at any time immersed therein. Anti-friction 65 trucks may be placed under these stiles, if desired, which will enable the fence to be raised more easily than it otherwise could.

The ropes or cords D are attached to the stiles c, and pass, one over sheaves b and the 70 other directly to the spool D', which is mounted in brackets B³ on the posts B. As will be readily seen, a turning of the crank d' of said spool will wind up or unwind the cords D, and thus elevate the fence or allow it to 75 descend, thus adjusting it to the desired position. The lever E forms another and in some cases a more desirable (because cheaper) means of raising the gate. It is provided with a hook, 80 e, which enters holes b² in the posts or strips, (see Figs. 3 and 4,) while its lower end engages under the lower ends of the stiles c, which, with the remainder of the fence, may thus be raised successively from one point to another. This may be regarded as an alternate means 85 of raising the gate when said gate is comparatively short and light; but in the longer and heavier gates it is properly a supplemental device, as the work of raising such gates is heavier than can be well accomplished by the 90 ropes and winding mechanism.

The fence, when raised, may be secured in position by any ordinary pawls or other engaging devices; but the friction of the stiles on the slides will be usually found sufficient 95 without other fastening, unless anti-friction trucks are employed.

The operation of my said invention may be briefly recapitulated as follows: The mud-sills and posts are placed in position, the gate (preferably composed of a stile, c, at each end and wires C connecting them, as shown) is mounted thereon, and adjusted to the proper distance above the water. When the water rises,

as is often the case, the gate is raised until it occupies the same relative position thereto as before; and when the water falls the gate is lowered correspondingly. The gate proper, being preferably constructed of wire or other small material, will offer little resistance to the water in case of a temporary sudden rise, when the gate cannot be conveniently adjusted soon enough to keep it therefrom.

10 Having thus fully described my said invention, what I claim as new, and desire to secure by Letters Patent, is—

15 1. The combination of a flood-gate consisting of stiles *c* and connecting-wires *C*, posts *B*, having slides, in which said stiles rest and are adapted to slide vertically, and the described means, consisting of the ropes *D*, sheaves *b*,

and spool *D'*, for raising and lowering the gates, substantially as shown and specified.

2. The combination, with the gate and the 20 gate-posts having holes therein, as shown, of the lever *E*, having hook *e*, as a supplemental means of raising the gate, said hook being adapted to engage in said holes, and the point of the lever to engage under the stiles of said 25 gate, substantially as set forth.

In witness whereof I have hereunto set my hand and seal, at Indianapolis, Indiana, this 12th day of September, A. D. 1882.

GEORGE W. FRANCIS. [L. S.]

In presence of—

C. BRADFORD,

E. W. BRADFORD.
